United States Patent Office

Des. 219,727
Patented Jan. 19, 1971

219,727

COMBINED BOTTLE AND CLOSURE THEREFOR

Richard L. Weckman, Perrysburg, Ohio, assignor to Owens-Illinois, Inc., Toledo, Ohio, a corporation of Ohio

Filed Feb. 19, 1968, Ser. No. 10,631

Term of patent 14 years

Int. Cl. D9—01

U.S. Cl. D9—144

FIG. 1

FIG. 3

FIG. 1 is a front elevational view of a combined bottle and closure showing my new design therefor;

FIG. 2 is a side elevational view thereof; and

FIG. 3 is a top plan view thereof.

The side not shown is the same in appearance as the side shown.

I claim:

The ornamental design for a combined bottle and closure therefor, substantially as shown and described.
